LOCKING ENVELOPE OR THE LIKE

Thomas E. Walsh, Cohoes, N. Y., assignor to
 Cohoes Envelope Company, Inc., Cohoes, N. Y.,
 a corporation of New York

Application November 20, 1945, Serial No. 629,835

3 Claims. (Cl. 229—77)

1

My present invention relates to locking devices, and more particularly to locking devices for envelopes, or other flat enclosures.

My improved locking device is intended to replace the present day envelope locking devices, such as metal clasps, twine and the like, which tend to become loose or to become entangled with other envelopes or closures. This is particularly true with regard to present day envelopes or closures intended to be used to send letters, papers, or merchandise through the mails.

In carrying out my invention, I employ a locking device consisting of but two parts, both of which act as a reinforcing means for the envelope or closure itself, one of such parts, including the locking tongue, being attached to the envelope or closure in its entirety, while the other part, including the member that cooperates with the locking tongue, is attached to both the envelope or closure and to the closing flap of the envelope or closure.

The principal object of my invention therefore, is an improved locking device for envelopes and other like closures.

Another object of the invention is an improved locking device for envelopes and other like closures manufactured from sheet material, such as paper, in which there will be no parts extending outwardly from the plane of such material when the device is in locking position.

Other objects and advantages of the device will appear as the description of the invention progresses.

In the accompanying drawing illustrating a preferred embodiment of my invention:

Figure 1 is a fragmentary perspective view at the open mouth of an envelope or other container equipped with locking means in accordance with my invention;

Figure 2 is a fragmentary elevation showing the closing flap on one wall portion of the envelope folded over upon the locking tongue of the opposite wall portion of the envelope, but prior to engaging said tongue in the locking opening of said flap;

Figure 3 is a view similar to Fig. 2, but showing the parts interlocked, and

Figure 4 is a section on the line 4—4 of Fig. 3.

Referring to the drawings, there is shown an envelope or like container, comprising a portion 10 and a portion 11 having formed therewith a closing flap or tab 12. The joining between the portion 11 and the closing flap or tab 12 is along a weakened line 13.

Secured to the portion 10, on the face thereof

adjacent the portion 11, is a reinforcing member 14 having cut therein and in portion 10 a locking tongue 15. The locking tongue 15 is formed as shown in Figure 3, with curved members 16 extending laterally from the body of the tongue 15 and with rounding extensions 17 at its upper end. The tongue 15 may be flexed, relative to member 14, along the dotted line 18.

Secured to the portion 11 and the tab or closure 10 flap 12, and on the face thereof adjacent the portion 10, is a reinforcement 19. In this reinforcement 19, and in the portion in engagement with the tab or closure flap 12 is a cut out portion 20, while in the reinforcement portion in engagement with the portion 11 of the envelope is a cut out portion 21. The cut out portion 20 has parallel sides defining an opening less in width than the distance between the limits defined by the curved members 16 of the locking tongue 15. The cut out portion 21 has rounded ends defining a space of a width less than the distance between the rounded projections 17 of the locking tongue 15.

In operating the locking device, the flap or tab 12 is folded over on the weakened line 13 so as to overlap the portion 10 of the envelope (see Fig. 2). The locking tongue is threaded through the cut out 20 so as to bring the curved portions 16 thereof into overlapping position outside the portion 10 (see Fig. 3) to establish a lock in this region of the structure, after which the projecting portions 17 thereof are placed under and in locking position with respect to the curved portions 21 in that portion of the cut out 20 lying in the portion 11 of the envelope to establish another lock in this region of the structure.

When thus assembled, the two portions 10 and 11 of the envelope, and the closing flap or tab 12, lie closely in engagement, with no projecting parts, and in practically a single plane.

From the foregoing description, taken in connection with the drawing, it will be evident that the tongue is doubly locked in position and will remain so locked in service.

To unlock the parts, it is simply necessary to release the portions 17 and 16, respectively, from their engagement with the parts of the structure with which they are interlocked, thereby freeing the tongue so that it may be withdrawn from the cut out 20 of the flap 12.

While I have described and illustrated a preferred embodiment of my invention, I recognize that many minor changes may be made in its construction and design without departing from its

essential features as defined in the appended claims.

Having thus described my invention, what I claim as new is:

1. An improved locking device for an envelope or like container of flexible sheet material, as paper, which has a flap on one wall thereof to be overfolded upon the opposite wall of the envelope, said locking device comprising a reinforcing sheet adhesively secured to the inner face of the flap and to the inner face of the envelope wall which carries said flap, said reinforcing material and flap and envelope wall having a portion thereof cut out to form an opening, said opening in the flap having its end remote from the mouth of the envelope substantially rectangular and having the sides thereof substantially parallel to each other, the end of said opening adjacent to the mouth of the envelope having formed at each end of the rectangular cut-out a pair of substantially semi-circular outwardly extending cut-outs, and in the wall of the envelope a substantially oval cut-out, the ends of such latter cut-out extending outwardly beyond the limits of the semi-circular cut-outs in the flap, a reinforcing sheet adhesively secured to the inner face of the other wall of the envelope, a tongue formed in said reinforcing sheet and in the upper end of the other wall of the envelope, said tongue having at its outer or free end a substantially oval member, the width of such member being greater than the width of the space between the outer limits of the space defined by the semi-circular cut-outs in the flap, said tongue having formed adjacent the oval member thereof outwardly extending members, the width of the tongue between the outer ends of the latter members being greater than the width between the parallel sides of the cut-out in the flap, and said tongue being integrally attached at its base to such other wall of the envelope whereby when the flap is folded over into overlapping engagement with such other wall of the envelope and the tongue threaded through the rectangular cut-out, the ends of the substantially oval member of the tongue may be tucked through the substantially oval cut-out in the flap and under the material of the flap adjacent thereto to establish a double lock for the envelope.

2. A double-walled envelope having a flap on one wall to be overfolded and locked against the opposite wall, said flap and its wall having a portion thereof cut out to form an opening, said opening in the flap having its end remote from the mouth of the envelope substantially rectangular and having the sides thereof substantially parallel to each other, the end of said opening adjacent to the mouth of the envelope having

formed at each end of the rectangular cut-out a pair of substantially semi-circular outwardly extending cut-outs, and in the wall of the envelope a substantially oval cut-out, the ends of such latter cut-out extending outwardly beyond the limits of the semi-circular cut-outs in the flap, a tongue formed upon the upper end of the other wall of the envelope, said tongue having at its outer or free end a substantially oval member, the width of such member being greater than the width of the space between the outer limits of the space defined by the semi-circular cut-outs in the flap, said tongue having formed adjacent the oval member thereof outwardly extending members, the width of the tongue between the outer ends of the latter members being greater than the width between the parallel sides of the cut-out in the flap, and said tongue being integrally attached at its base to such other wall of the envelope whereby when the flap is folded over into overlapping engagement with such other wall of the envelope and the tongue threaded through the rectangular cut-out, the ends of the substantially oval member of the tongue may be tucked through the substantially oval cut-out in the flap and under the material of the flap adjacent thereto to establish a double lock for the envelope.

3. An improved locking device for envelopes or other like closures, comprising a cut out portion formed as a unit in a wall of the envelope and in the closing flap therefor, and a tongue formed of a part of an opposite wall of the envelope, said tongue and cut out portion interlocking to firmly lock the envelope in closed position when the flap is overfolded upon said opposite wall of the envelope, the cut out in the flap being substantially rectangular and the cut out in the wall of the envelope which carries said flap being substantially oval, and the tongue having a rounded portion wider than the rectangular cut out and having an oval portion wider than the oval cut out and which portions establish a double locking engagement with said cut outs when the flap is overfolded and the tongue inserted through said cut outs.
